CLAIM

I claim the ornamental design for a vehicle document folder, as shown and described.

DESCRIPTION

FIG. 1 is a perspective view of the vehicle document folder.

FIG. 2 is a front view of the claimed design.

FIG. 3 is a rear view of the claimed design.

FIG. 4 is a left side view of the claimed design.

FIG. 5 is a right side view of the claimed design.

FIG. 6 is a top view of the claimed design; and,

FIG. 7 is a bottom view of the claimed design.

In the drawings, the broken lines depict environmental subject matter only and form no part of the claimed design.

1 Claim, 7 Drawing Sheets
